UNITED STATES PATENT OFFICE.

ADOLPH C. RECKER, OF OAKVILLE, CONNECTICUT, ASSIGNEE TO WATERBURY MFG. CO.,
OF WATERBURY, CONNECTICUT, A CORPORATION.

FLASH-LIGHT.

1,198,660.

Specification of Letters Patent. Patented Sept. 19, 1916.

Application filed June 19, 1916. Serial No. 104,383.

To all whom it may concern:

Be it known that I, ADOLPH C. RECKER, a citizen of the United States, residing at Oakville, in the county of Litchfield and 5 State of Connecticut, have invented a new and useful Improvement in Flash-Lights; and I do hereby declare the following, when taken in connection with the accompanying drawings and the characters of reference 10 marked thereon, to be a full, clear, and exact description of the same, and which said drawings constitute part of this application, and represent, in—

Figure 1 a side view of a flash light constructed in accordance with my invention. 15 Fig. 2 a side view partly in section, at a right angle to the position shown in Fig. 1. Fig. 3 a broken sectional view of the bottom portion of the lamp with the cap 20 partially screwed on. Fig. 4 an end view with the cap removed.

This invention relates to an improvement in flash lights of the portable type, and particularly to flash lights having round casings. 25 To hold the batteries in place and compensate for slight variations in length, it has been customary to insert a spring in the bottom of the cap which is applied to the lower end of the case which spring bears 30 upon the lower end of the battery.

The object of this invention is to employ a spring at this point which will serve not only to provide for varying lengths of batteries, but will become one of the terminals 35 and be permanently connected with the case; and the invention consists in the construction hereinafter described and particularly recited in the claims.

In carrying out my invention, I employ 40 the usual tubular case 4 containing the usual incandescent lamp, not shown, which is secured in place by a collar 5 screwed onto the upper end of the case and holding the usual magnifying lens 6. The lower 45 end of the case is closed by a cap 7 in substantially the usual way except in the cap is located a disk 8 of insulating material. The usual battery 9 is employed, which is inserted into the case the upper end being 50 in contact with the lamp. The lower end is engaged by a spring 10 hinged to a strap 11 riveted to the side wall of the case but insulated therefrom, the upper end 12 of the strap extending into the path of move-

ment of a switch plate 13 which is provided 55 with a button or finger-piece 14 extending outward through a slot 15 formed in a housing 16 secured to the case. The spring 10 is formed from a piece of wire doubled in the center around which central portion 60 17 the end of the strap 11 is folded so as to hinge the spring to the strap. The ends of the wire then extend substantially parallel to a point approaching the opposite wall of the casing when they are bent upward and 65 backward and their ends turned downward to form cam-surfaces 18 which bear upon the end of the battery 9 and so that when the cap 7 is screwed into place, these cam-surfaces 18 bearing on the end of the bat- 70 tery will cause the end of the strap 11 to move away from the side of the casing and hold that strap out of contact with the side wall of the case. The spring is readily folded outward to give clearance for the 75 entrance or removal of the battery. When the cap 7 is screwed into place the spring is insulated from the case until the switch plate 13 is moved to close contact through the case strap 11 and spring 10 with the 80 battery.

I claim:

1. A flash light comprising a casing, a strap secured at its upper end to one side of the casing and insulated therefrom, a 85 spring hinged to the lower end of the strap, and a cap closing the lower end of the casing and forming a bearing for the spring.

2. In a flash light, the combination with a metallic casing and battery, of a strap secured to one side of the casing and insulated therefrom, a spring hinged to the lower end of said strap, said spring adapted to be turned against the lower end of the battery, a cap secured to the lower end of the case 95 and crowding the said spring against the lower end of the battery, and a switch adapted to connect and close the circuit from the upper end of the strap to the casing.

3. A flash light comprising a tubular metallic casing, a strap secured to the side wall of the casing and insulated therefrom and extending to the lower end thereof, a spring hinged to the lower end of the strap, said 105 spring formed with cam-surfaces adapted to bear upon a battery, a cap closing the lower end of the casing and tending to

crowd the spring into the casing, and means for closing the circuit from the upper end of the strap to the casing.

4. A flash light comprising a tubular metallic casing supporting an incandescent lamp at one end and closed by a cap at the opposite end, a battery in said casing and in contact with said lamp, a strap secured to the side wall of the casing and insulated ¹⁰ therefrom, said strap extending to the lower

end of the casing, a spring hinged to the lower end of said strap the ends of the said spring formed with cam-surfaces adapted to bear against the battery cell, a disk of insulating material in the cap against which ¹⁵ the spring bears, and a switch adapted to electrically connect the upper end of the strap with the casing.

ADOLPH C. RECKER.
